[57] CLAIM

The ornamental design for a fish lure, as shown and described.

DESCRIPTION

FIG. 1 is a perspective view of a fish lure embodying my new and ornamental design;

FIG. 2 is a bottom plan view thereof;

FIG. 3 is a side elevational view thereof;

FIG. 4 is a front elevational view thereof;

FIG. 5 is a rear elevational view thereof; and

FIG. 6 is a top plan view thereof.

The broken line showing of a fishing line is for illustrative purposes only and forms no part of the claimed design.

FIG. 1**FIG. 2****FIG. 4****FIG. 3****FIG. 5****FIG. 6**
